Primary Examiner — Gene Kim*Assistant Examiner* — Michael Dennis(74) *Attorney, Agent, or Firm* — Edell, Shapiro & Finn, LLC(57) **ABSTRACT**

A toy with repositionable portions is disclosed. The toy may be stylized as a toy figure that may include a leg section and a torso section. The leg section includes legs pivotally coupled to a pelvic section. The pelvic section may also include an upward-extending connection post. The torso section, furthermore, may include a body cylinder that connects to the connection post. The body cylinder includes a series of resilient tabs that slidingly engage the post, securing the sections together while permitting the rotation of the torso section about the post. With this configuration, the toy figure possesses multiple degrees of motion, being adapted to move in bending and twisting motions.

POSABLE TOY AND METHOD OF FORMING

CROSS REFERENCE TO RELATED
APPLICATIONS

This application is a continuation of U.S. Nonprovisional application Ser. No. 11/847,729, filed 30 Aug. 2007 and entitled "Posable Toy and Method of Forming," which is a nonprovisional of U.S. Provisional Application No. 60/824,305, filed 1 Sep. 2006 and entitled "Posable Toy and Method of Forming." The disclosures of the aforementioned applications are incorporated herein by reference in their entireties.

FIELD OF THE INVENTION

The present invention is directed toward a posable/repositionable toy and, in particular, to a toy figure with posable/repositionable portions adapted to be repositionable along numerous degrees of freedom, including, but not limited to, rotation about vertical and horizontal axes.

BACKGROUND OF THE INVENTION

The U.S. Government has issued "small parts" requirements for toys and products intended for use by children under three years of age. These requirements are published in the Code of Federal Regulations in Title 16, Parts 1501 and 1500.50, 51, 52 and 16 C.F.R. 1500.18(a)(9). This regulation is intended to prevent deaths and injuries to children under three from choking on, inhaling, or swallowing small objects they may "mouth". It bans toys and other articles that are intended for use by children under three and that are or have small parts, or that produce small parts when broken.

A "small part" is any object that fits completely into a specially designed test cylinder (2.25 inches long by 1.25 inches wide) that approximates the size of the fully expanded throat of a child under three years old. This specialized definition applies to (1) a whole toy or article; (2) a separate part of a toy, game, or other article; and (3) a piece of a toy or article that breaks off during testing that simulates use or abuse by children. If a "small part" fits completely into the specially designed test cylinder, and the toy or product from which it came is intended for use by children under three years of age, the toy or product is banned because the small part presents a choking hazard.

Thus, toys and products intended for use by children under three years of age must not release pieces that fit completely into the small parts cylinder after impact, flexure, torque, tension, and compression testing. These tests simulate the forces that toys and products can/may experience during normal use and abuse by children under three years of age. If these forces cause parts to break off that fit in the small parts cylinder, those parts are deemed to present a risk of choking, aspiration, or ingestion to children under three years of age.

There are a number of commercially available toys having posable/repositionable portions. Generally, these toys are stylized as character figures designed for use by preschool children. One drawback to some of these pre-existing toy figures is that the various posable/repositionable portions (e.g., the legs, the arms, the head, the torso, etc.) are made of small parts that are connected in such manner that they are capable of being too easily separated. Due to safety concerns, there has been increased awareness regarding the safety of such toy figures (due to the fact that preschool children may be able to separate the portions of the figure, which may result in injury to the child should one of the portions be swallowed).

2

Thus, it is desirable to provide a toy, having posable/repositionable portions, with a generally integral structure that prevents the posable/repositionable portions from being too easily separated.

5 SUMMARY OF THE INVENTION

The present invention generally is directed toward a posable/repositionable toy and, in particular, to a toy figure with posable/repositionable portions adapted to be repositionable along numerous degrees of freedom, including, but not limited to, rotation about vertical and horizontal axes. A toy figure in accordance with the present invention may include a lower or first assembly and an upper or second assembly. The lower assembly may include legs pivotally coupled to a pelvic section. The pelvic section may include an upward-extending connection post. The upper assembly may include a spine and body cylinder, both of which may be rotatably mounted on the upward-extending connection post. An external figure body may be secured to the spine and body cylinder. Thus, the external figure body, the spine, and the body cylinder may be rotated with respect to the lower assembly. With this configuration, a toy figure in accordance with the present invention possesses multiple degrees of freedom, being adapted to move in bending and twisting motions.

25 BRIEF DESCRIPTION OF THE DRAWINGS

FIG. 1 illustrates an exploded view of a posable toy according to an embodiment of the present invention.

FIG. 2A illustrates an isolated, exploded view of the lower assembly of the posable toy of FIG. 1.

FIG. 2B illustrates an isolated, perspective view of the lower assembly of the posable toy of FIG. 1.

FIG. 3A illustrates an isolated, perspective view of the body cylinder shown FIG. 1.

FIGS. 3B and 3C illustrate isolated views of the lower assembly, showing the connection of the body cylinder to the lower assembly.

FIG. 4A illustrates an isolated, perspective view of the spine shown in FIG. 1.

FIG. 4B illustrates the body cylinder of FIG. 3A coupled to the spine of FIG. 4A.

FIG. 4C illustrates an isolated view of the upper assembly shown in FIG. 1, with the spine/body cylinder illustrated in phantom.

FIG. 5 illustrates an exploded view of the upper and lower assemblies of the posable/repositionable toy of FIG. 1, showing the connection of the upper assembly to the lower assembly.

FIG. 6 illustrates a perspective view of the assembled posable/repositionable toy of FIG. 1.

FIG. 7 illustrates an exploded view of a posable/repositionable toy according to another embodiment of the present invention.

FIGS. 8A and 8B illustrate front perspective views of the lower assembly of the posable/repositionable toy of FIG. 7, showing the connection of an accessory article of clothing to the lower assembly.

FIG. 9 illustrates a front perspective view of the posable/repositionable toy of FIG. 7, showing the assembled figure and the capturing of the accessory article of clothing between the upper and lower assemblies.

Like reference numerals have been used to identify like elements throughout this disclosure.

65 DETAILED DESCRIPTION OF THE INVENTION

In accordance with the present invention, a toy with posable/repositionable portions is disclosed. FIG. 1 is an

exploded view of a posable/repositionable toy in accordance with an embodiment of the present invention. As shown, the posable/repositionable toy may comprise a FIG. 100 including a first or lower assembly 200 and a second or upper assembly 300. The components of the lower assembly 200 and upper assembly 300 may be formed from materials including, but not limited to, plastics/thermoplastics such as acrylonitrile butadiene styrene (ABS) and/or polyvinyl chloride (PVC), as well as natural materials such as wood. In one embodiment of the present invention described herein, the lower assembly 200 and the upper assembly 300 are formed utilizing a combination of ABS and PVC components. The components may be formed utilizing, e.g., conventional molding processes such as blow molding, injection molding, insert molding, over-molding, etc.

The lower assembly 200 may include a support or leg section 210 and a base or pelvic section 220. The base section 220 may include a bore or channel (extending, e.g., generally horizontally through the pelvic section 220), as well as a connection post 260 extending, e.g., generally vertically from the base section 220. The connection post 260 is configured to mate with the upper assembly 300. In the illustrated embodiment, the upper (distal) end of the connection post 260 includes a flange or rim 262 and a recessed portion 264 extending about its periphery. The recessed portion 264, in combination with the rim 262, forms a shoulder or ledge 265 that serves as a stop, preventing the separation of the upper assembly 300 from the lower assembly 200. With this configuration, the post 260 may rotatably capture the body cylinder 360 of the upper assembly 300 when mounted onto to the connection post 260 (described in greater detail below).

FIG. 2A is an exploded view of the lower assembly of the posable/repositionable toy of FIG. 1. Referring to FIG. 2A, the leg section 210 of the lower assembly 200 may include a first leg member 212 coupled to a second leg member 214 via a rod 216. The base section 220 may include a front waist portion 230 and a rear waist portion 240. The front 230 and rear 240 waist portions may each include a cut-out area 225 that form a bore or channel when the waist portions 230, 240 are connected. To form the lower assembly 200, the cut-out areas 225 of the waist portions 230, 240 are aligned such that the rod 216 of the leg section 210 is positioned within the cut-out areas 225. FIG. 2B is an isolated view of the lower assembly of the posable/repositionable toy of FIG. 1. As shown in FIG. 2B, the waist portions 230, 240 may be permanently secured to each other (e.g., via solvent welding) by capturing the rod 216 of the leg section 210 in the newly-formed bore 250.

Utilizing this construction, the rod 216 of the leg section 210 may be configured to move within the bore formed by the connected portions 230, 240 with the base section 220 pivoting about the rod 216. The connection of the leg section 210 to the base section 220 is not limited to the embodiment illustrated herein. For example, in another embodiment, the base section 220 may be formed from a unitary structure (e.g., the base section 220 may be over-molded onto the leg section 210 (not illustrated)). Although any suitable materials may be utilized, in the illustrated embodiment, the base section 220 (including waist portions 230, 240) may be formed from ABS, while the leg section 210 may be formed from PVC.

Referring back to FIG. 1, the upper assembly 300 may include a figure upper body 310 including a torso 320, arms 330, and a head 340. The upper assembly 300 may further include a core member or spine 350 and a body cylinder or cap 360 (also called a plug). The body cylinder 360 may include a structure configured to rotatably connect to the connection post 260 of the lower assembly 200, securing the spine 350 of

the upper assembly 300 to the lower assembly 200. FIG. 3A is an isolated perspective view of the body cylinder 360. In the embodiment illustrated, the body cylinder 360 includes a base 362 with a wall or flange 364 extending upward about the periphery of the base 362. A channel or bore 366, concentrically disposed with respect to the flange 364, may be defined by a series of angularly spaced, resilient tabs 368.

The dimensions of the channel 366 may be chosen such that the tabs 368 slidably, yet securely engage the connection post 260 of the lower assembly 200. Referring to FIGS. 3B and 3C, the channel 366 of the body cylinder 360 receives the post 260 of the lower assembly 200. Specifically, the connection post 260 of the lower assembly 200 may be axially urged into the channel 366 of the cylinder body 360. The resilient tabs 368, beginning in their normal position, initially flex outward to permit passage of the connection post 260 and/or rim 262. However, once the tabs 368 become positioned below the rim 262 and within the recessed portion 264, the tabs 368 return to their normal (un-flexed) position. In this position, the passage of the rim 262 back through the channel 366 is prevented—the rim 262 cannot pass back through the channel 366 without a very large force being applied to the two parts (i.e., a force larger than a child is capable of exerting during play or product abuse). When the tabs 368 return to their normal, un-flexed position, the shoulder 265 acts as a stop, preventing the passing of the post 260 through the channel 366. This attachment arrangement prevents the removal of the body cylinder 360 from the connection post 260. However, since the resilient tabs 368 slidably engage the post 260, the body cylinder 360 may be rotated about the post 260.

The spine 350 supports the figure body. As seen best in FIG. 4A, the spine 350 may include a cylindrical shaft 352 terminating in a socket 354 operable to mate with the body cylinder 360. The socket includes a lip 356 extending about the perimeter of the socket opening. In operation (as illustrated in FIG. 4B), the spine 350 may be inserted axially onto the body cylinder 360 until the socket 354 of the spine 350 engages the flange 364 of the body cylinder 360. The lip 356 becomes positioned between the gap existing between the wall 364 and the tabs 368 of the body cylinder 360 (see FIG. 3A). In this manner, when the socket 354 is seated on the cylinder 360, the lip 356 may further compress the resilient tabs toward the connection post, which, in turn, makes separation of the lower assembly 200 from the upper assembly 300 more difficult. The body cylinder 360 may be permanently secured to the spine 350 using techniques such as solvent welding. The combined (connected) spine/cylinder structure is illustrated in FIG. 4B.

Referring to FIG. 4C, the figure body 310 is secured to the combined spine/cylinder structure (e.g., it may be formed over the spine 350 via molding). Since the body cylinder 360 rotatably engages the connection post 260, the spine 350, fixed to the figure body 310, may also rotate about the axis defined by the connection post 260. Although any suitable materials may be utilized, in the illustrated embodiment, the spine 350 (including the cylindrical shaft 352 and the socket 354) and the body cylinder 360 (including the base 362, the flange 364, and the tabs 368) may be formed from ABS, while the figure body 310 (including the torso 320, the arms 330, and the head 340) may be formed from PVC.

The method of forming the posable/repositionable toy 100 is explained with reference to FIGS. 2-5. Initially, as shown in FIGS. 2A and 2B, the leg section 210 may be coupled to the base section 220 as described above. Then, the spine 350 may be coupled to the body cylinder 360 as described above (FIG. 4B), and the figure body 310 may then be over-molded onto the combined spine/cylinder 350/360 structure, fixing the

5

figure body 310 thereto (FIG. 4C). Finally, as shown in FIG. 5, the upper assembly 300 may be coupled to the lower assembly 200. As explained above, the body cylinder 360 of the upper assembly 300 mates with the post 260 of the lower assembly 200, with the tabs 368 engaging the post 260 as described above. This provides a substantially permanent connection between the upper assembly 300 and the lower assembly 200, while enabling the movement (for example, rotation) of the upper assembly with respect to the lower assembly (and vice versa).

In this manner, the present invention allows for the production of a posable/repositionable toy 100 without the use of conventional fasteners (screws, bolts, rivets, etc., all of which may be categorized as "small parts" for a product designed for children under three years of age), while providing a toy 100 that may be posed/repositioned along plural degrees of freedom. Referring to FIG. 6, the leg section 210 is adapted to rotate about the base section 220 (e.g., about a horizontal axis) to create a bending motion of the toy 100 (indicated by arrow B). Additionally, as indicated by arrow R, the figure body 310 (and the entire upper assembly 300) is adapted to rotate with respect to the entire lower assembly 200 (e.g., about a generally vertical axis) to create a twisting motion of the toy 100.

An accessory item may also be positioned onto the lower assembly 200 such that it becomes captured between the lower assembly 200 and the upper assembly 300. FIGS. 7-9 illustrate a posable toy 100 in accordance with another embodiment of the present invention. Referring to FIG. 7, the posable toy 100 includes a general structure similar to that described above with reference to FIGS. 1-6, having a lower assembly 200 and an upper assembly 300 overmolded with a figure body 310. In addition, the posable toy 100 further includes an accessory 700 in the form of an article of clothing. The article of clothing may include any decorative or functional accessory including, but not limited to, dresses, pants, shorts, belts, skirts, weapons, bags, etc. The accessory may be formed from materials including, but not limited to, soft-goods (e.g., cloth), plastic, wood, etc.

Referring to FIGS. 8A and 8B, it can be seen the accessory 700 may include an aperture 710 with dimensions slightly larger than the dimensions (e.g., diameter) of the connection post 260. The connection post 260 is inserted through the aperture, positioning the accessory 700 onto the lower assembly 200 as illustrated in FIG. 8B. The upper assembly 300 may then be secured to the connection post 260 as described above, with the body cylinder 360 pressing the accessory 700 against the lower assembly 200. In this manner the accessory 700 is non-removably trapped between the upper assembly 300 and the lower assembly 200, securing it to the toy 100 (FIG. 9).

While the invention has been described in detail and with reference to specific embodiments thereof, it will be apparent to one skilled in the art that various changes and modifications can be made therein without departing from the spirit and scope thereof. For example, the posable/repositionable toy can be of any size and shape, and may be formed from any suitable materials. Though the connection structure has been illustrated with regard to waist/torso and leg/torso components, the structure may be easily adapted for other articulated portions such as head/torso, arm/torso, etc. In addition, the disclosed connection mechanism/method may be applied to other toy products (e.g., vehicles, animals, buildings, play sets etc.). Thus, it is intended that the present invention cover the modifications and variations of this invention that come within the scope of the appended claims and their equivalents.

6

It is to be understood that terms such as "left", "right", "top", "bottom", "front", "rear", "side", "height", "length", "width", "upper", "lower", "interior", "exterior", "inner", "outer" and the like as may be used herein, merely describe points of reference and do not limit the present invention to any particular orientation or configuration.

We claim:

1. A connection system for toy figure portions, the connection system comprising:
  - a first assembly including a support post; and
  - a second assembly including:
    - a plug coupled to the support post, the plug comprising a plurality of resilient tabs configured to engage the support post, and
    - a shaft having a socket that receives the resilient tabs, wherein the socket mates with the plug such that the socket captures the resilient tabs against the support post.
2. The connection system of claim 1, wherein:
  - the support post comprises a recessed area formed into its surface; and
  - the resilient tabs are positioned within the recessed area when the plug is mated with the socket.
3. The connection system of claim 1, wherein:
  - the support post includes an end having a rim defining a shoulder; and
  - the tabs are positioned below the rim such that the rim inhibits separation of the plug from the support post.
4. The connection system of claim 3, wherein:
  - the first assembly comprises a platform;
  - the support post extends from the platform, the support post including a distal end; and
  - the rim is disposed along the support post distal end.
5. The connection system of claim 1, wherein:
  - the plug further comprises:
    - a base, the tabs extending from the base;
    - a plug wall extending distally about a perimeter of the base, the plug wall being generally coaxial with respect to the tabs and spaced therefrom to form a gap between the plug wall and the tabs;
    - the socket comprises a lip extending distally from the socket; and
    - the lip is positioned within the gap such that the lip engages the tabs, compressing the tabs against the support post.
  6. The connection system of claim 1, wherein the first assembly comprises a leg section rotatably coupled to the support post, the leg section including:
    - a first leg member;
    - a second leg member; and
    - a rod connecting the first leg member to the second leg member.
  7. The connection system of claim 1, wherein:
    - the plug is rotatably coupled to the support post; and
    - the socket is connected to the plug such that the socket rotates with respect to the support post.
  8. The connection system of claim 1, wherein:
    - the plug comprises a plug base;
    - the resilient tabs extend from the plug base such that the tabs are angularly spaced about the plug base;
    - the plug base further includes a plug wall extending from the plug base; and
    - the plug wall surrounds the resilient tabs.
  9. The connection system of claim 8, wherein:
    - the plug wall defines a wall perimeter; and
    - a portion of the plug base extends beyond the wall perimeter.

- 10.** A connection system for toy figure portions, the connection system comprising:
- a post;
- a plug rotatably mounted onto to the post, the plug comprising a plug base and a plurality of tabs extending from the plug base, the plug further including a plug bore operable to receive the post such that the plurality of tabs surrounds the post; and
- a support member comprising a shaft portion and a socket portion, wherein the support member is connected to the plug such that socket portion receives the post and the plurality of tabs extends from the plug base, 10 wherein the socket portion is configured to capture the resilient tabs against the post.
- 11.** The connection system of claim **10**, wherein:
- the post extends distally from a post base, the post including a proximal end and a distal end;
- the plurality of tabs is spaced about the plug bore;
- each of the plurality of tabs includes a proximal end and a 20 distal end; and
- the distal end of the post extends through the plug bore such that the post distal end is positioned above the distal ends of the tabs.
- 12.** The connection system of claim **11**, wherein:
- the plug further comprises a plug wall extending from the plug base; and
- the plug wall surrounds the plurality of tabs and is spaced from the tabs to define a gap therebetween.
- 13.** The connection system claim **12**, wherein:
- the plug wall defines a wall perimeter; and
- a portion of the plug base extends beyond the wall perimeter.
- 14.** The connection system of claim **12**, wherein:
- the socket portion further includes socket flange that is positioned within the gap; and
- the socket flange compresses the plurality of tabs against the post.

- 15.** A toy comprising:
- a first toy portion; and
- a second toy portion,
- wherein the first toy portion is movably coupled to the second toy portion via a connection system comprising:
- a first assembly including a support post; and
- a second assembly including:
- a plug rotatably coupled to the support post, the plug comprising a plurality of resilient tabs configured to engage the support post,
- a shaft having a socket that receives the resilient tabs, wherein the socket mates with to the plug such that the socket captures the resilient tabs against the support post.
- 16.** The toy of claim **15**, wherein:
- the toy comprises a toy figure;
- the first toy portion includes a torso;
- the second toy portion includes a leg assembly; and
- the connection system permits rotation of the torso with respect to the leg assembly.
- 17.** The toy of claim **16**, wherein:
- the leg assembly includes a platform, a first leg member, and a second leg member;
- the support post of the first assembly extends from the platform; and
- the shaft of the second assembly supports the torso.
- 18.** The toy of claim **17**, further comprising a toy figure accessory mounted on the support post and disposed between the platform and the plug.
- 19.** The toy of claim **15**, wherein:
- the plug comprises a plug base;
- the resilient tabs extend from the plug base, the tabs being angularly spaced about the plug base; and
- the plug base further includes a plug wall extending from the plug base, the plug wall surrounding the plurality of resilient tabs.
- 20.** The toy of claim **19**, wherein:
- the plug wall defines a wall perimeter; and
- a portion of the plug base extends beyond the wall perimeter.
